PUMPING MECHANISM

Filed Oct. 6, 1931

UNITED STATES PATENT OFFICE

HJALMAR T. BLOM, OF MICHIGAN CITY, INDIANA, ASSIGNOR TO SULLIVAN MACHINERY COMPANY, A CORPORATION OF MASSACHUSETTS

PUMPING MECHANISM

Application filed October 6, 1931. Serial No. 567,240.

My invention relates to pumping mechanisms, and more particularly to air compressors and unloading means therefor. One of the standard methods of unloading air compressors is by connecting the interior of the cylinder continuously with the atmosphere, as through the compressor intake, when it is desired to interrupt the pumping action. A usual method of accomplishing this result is to open, and hold in open position, the inlet valves of the compressor which is to be unloaded. In large-size compressors, where the volume of air handled is very great, it is obviously necessary, in order that the power lost through drawing in and discharging air through the inlet valves while the compressor is unloaded may be kept at a minimum, to provide devices for opening large numbers of inlet valves, and accordingly multiplication of parts is encountered. Obviously, moreover, it would be beneficial to avoid this multiplication of parts and to attain, at the same time, maximum freedom of flow inwardly and outwardly with respect to the compressor cylinder.

It is an object of my invention to provide an improved pumping mechanism. It is another object of my invention to provide an improved unloading mechanism for a compressor which permits practically free communication between the interior of the cylinder and the atmosphere during periods of unloading. It is a further object of my invention to provide an improved unloading mechanism for a compressor in which with a single valve, even in large size compressors, an end of a compressor may be wholly unloaded according to the method by which the interior of the compressor is connected freely with the atmosphere. It is a further object of my invention to provide an improved unloading mechanism for air compressors which may be employed with equal facility in single stage and multi-stage compressors, and in which either manual or automatic control may be selectively availed of. Other objects and advantages of the invention will subsequently appear.

In the accompanying drawing, in which, for purposes of illustration, I have shown

one form which my invention may assume in practice,—

Fig. 1 is a side elevation of a compound compressor in which the illustrative embodiment of the invention is incorporated;

Fig. 2 is an axial section through the low pressure cylinder of the air compressor, illustrated in Fig. 1, the section being taken on a plane corresponding to the line 2—2 of Fig. 3, with parts removed;

Fig. 3 is a vertical transverse section taken on line 3—3 of Fig. 2;

Fig. 4 is an elevation of a valve;

Fig. 5 is a section through the unloading mechanism operating devices taken on the line 5—5 of Fig. 3.

Referring to the drawing, and particularly Fig. 1, it will be noted that an air compressor 1 having a low pressure cylinder 2 and a high pressure cylinder 3 connected through an intercooler 4, is arranged to take air through an intake connection 5 and deliver it after compression to a discharge line 6. The low pressure cylinder, whose details of construction alone are illustrated, comprises a cylinder member 7 having a bore 8 within which a piston 9 is reciprocable by a piston rod 10. Heads 11, of which one is shown in section in Fig. 2, comprises spaces 12 in communication, as at 13, with a chamber 14 in the cylinder casting which communicates freely with the intake 5 of the compressor. Combined inlet and discharge valve units, generally designated 15, are arranged at the top and around substantial portions of the sides of the cylinder head, a large number of these units being used in view of the size of the compressor and the importance of maintaining the velocity of air flow through the ports as low as possible. These combined inlet and discharge valve units communicate with the bore of the cylinder through ports 16. Each of these units comprises an inlet valve unit 17 and a discharge valve unit 18, and the discharge side of the latter communicates with a chamber 19 in the cylinder casting, which chamber is connected, as at 20, with the intercooler 4. The inner wall 22 of each head member 11 is provided with an arcuately arranged series of passages 23 which open through an annular

plane seat surface 24 preferably slightly recessed within the forward inner surface of the head member. To control flow through the ports 23, an annular valve member 25 having a series of ports 26 arcuately arranged therein and having intermediate passage closure portions 27, is supported in contact with the seat surface 24. The valve member 25 may preferably be formed of saw steel or the like, and 10 may be reinforced, if desired, either at its inner or outer peripheries by a strengthening ring. Such a ring is shown at 28 secured at the inner periphery of the valve 25 in Figs. 2 and 4. To insure that the valves 25 will remain upon their seats, guides 29 secured, as by screws 30, to the inner side of the heads 11, may be employed, if desired, these guides having lips 31 overlapping an edge of the valve. These guides may be arranged either 15 at the inner periphery, at the outer periphery, or to cooperate with both peripheries of the valves.

To control the position of the valves 25, combined manually operable and automatically operable controlling means are provided. Herein, secured to each of the valve discs 25 I have shown arcuate racks 32 with which beveled pinions 33 carried on radially extending shafts 34 cooperate. The outer ends of the shafts 34 carry spur gears 35, and a rack 36 engages each pinion 35. The racks are carried by plunger members 37 normally held by a spring 38 in a position to maintain the valves 25 in port-closing position. The plungers 37 are reciprocable in cylinder members 40 carried by the heads 11, and the plungers are formed at one end as pistons; herein in Fig. 5 the plunger being shown as provided with a double packed cup washer type piston 41. It is obvious that since, in the high pressure cylinder at least, there is a possibility of air escaping to the interior of the cylinders 40 at intercooler pressure, it is desirable that the pistons preclude the flow of air in both directions. Other packing devices obviously may be used, and if desired the plunger 37 may be arranged to cooperate with a valve seat when in its position shown in Fig. 5. The plunger 37 may be manually moved, if desired, by the handle 43 and screw 44, whose inner end is adapted to engage the right hand side of the piston in Fig. 5. A lock nut 46 may hold the parts in any desired position.

To permit automatic control of the plungers 37, a pilot valve 47 receiving air through a passage 48 from the discharge line of the compressor is provided to supply air to operate the plungers 37 when the compressor discharge pressure passes a predetermined desired maximum and to vent the air previously supplied when the compressor discharge pressure falls below a predetermined desired minimum. The pilot valve 47 controls in this manner the flow of air through a passage 49 which is connected by pipes 50, 51 and

branch connections 52, 53 and 54, 55 with the unloading plungers 37 associated with the low and high pressure cylinders respectively.

The description heretofore given has related primarily to the details of construction of but one end of the low pressure cylinder; but obviously both ends of this cylinder may be similarly equipped, and both ends of the high pressure cylinder may be provided with generally similar unloading devices for the purpose of connecting the interior of the high pressure cylinder constantly with the intercooler during unloading, and such mechanisms are shown in connection with the high pressure cylinder, generally at 56, 57, supplied with fluid through the pipes 54, 55.

It will be understood from what has been said that when it is desired that the compressor shall operate in a normal manner and draw in and compress air to a desired discharge pressure, the valves 25 will be positioned upon their seats 24 in such manner that the port closure portions 27 overlie the passages 23; and with the valves in that position air will be drawn through the intake 5, the chamber 14, passage 13, chamber 12, the inlet valve unit 17, into the cylinder through ports 16, be compressed therein, discharged through discharge valve units 18 to chamber 19 and through passage 20 to the intercooler 4, from which it will be drawn into the high pressure cylinder 3 and there compressed in a manner which will be clear from what has been described with respect to the low pressure cylinder. When the compressor is unloaded, which may be effected by manual rotation of the screw 44, or which may be effected automatically when the compressor discharge pressure exceeds the predetermined maximum limit, the plungers 37 will be moved in their cylinders against the pressure of the springs 38, and the racks 36 will rotate the gears 35, the shafts 34, the pinions 33, and thereby actuate the arcuate racks 32 and move the valve elements 25 to bring the ports 26 therein into alignment with the passages 23 in the cylinders heads; and thereupon the interior of the low pressure cylinder will be placed in free communication, through the ports 26 and passages 23, chamber 12, passage 13, chamber 14, and intake connection 5, with the atmosphere and correspondingly the high pressure cylinder bore will be placed in free communication with the interior of the intercooler in a manner which will be obvious.

It will be clear that by the mechanism described and illustrated, I have provided a very simple, desirably controlled and very efficient unloading mechanism, in which single movable valves provide communication of large flow area between the cylinder bore and the spaces with which their intakes communicate. It will be evident that the

mechanism is inexpensive, comprises a minimum number of parts, is not likely to reduce efficiency by reason of leakage, but instead, because of its simplicity and the moderate flexibility of the valves, to insure a tight seal when the unloading valves are in closed position. It will further be noted that not only are the large numbers of individual unloading devices associated with separate inlet valves eliminated, but that the most direct possible flow between the interior of each cylinder and its intake space is provided.

While I have in this application specifically described one form which my invention may assume in practice, it will be understood that this form is shown for purposes of illustration only and that the invention may be modified and embodied in various other forms without departing from its spirit or the scope of the appended claims.

What I claim as new and desire to secure by Letters Patent is:

1. In a compressor, in combination, a cylinder having a head, means associated with said cylinder for controlling the inlet of fluid thereto and the discharge of fluid therefrom during normal operation, and separate compressor unloading means for providing a direct communication between the interior of said cylinder and a space at its intake pressure including a rotatable unloading valve coaxial with said head and carried thereby and having operating means.

2. In a compressor, in combination, a cylinder, means associated therewith for controlling the inlet of fluid thereto and the discharge of fluid therefrom during normal operation, and separate compressor unloading means for providing a direct communication between the interior of said cylinder and a space at its intake pressure including a rotatable unloading valve coaxial with said cylinder.

3. In a compressor, in combination, a cylinder, means associated therewith for controlling the inlet of fluid thereto and the discharge of fluid therefrom during normal operation, and separate compressor unloading means for providing a direct communication between the interior of said cylinder and a space at its intake pressure including a rotary

disc unloading valve coaxial with said cylinder.

4. In a compressor, in combination, a cylinder, means associated therewith for controlling the inlet of fluid thereto and the discharge of fluid therefrom during normal operation, and separate compressor unloading means for providing a direct communication between the interior of said cylinder and a space at its intake pressure including a ported rotary disc unloading valve coaxial with said cylinder.

5. In a compressor, in combination, a cylinder member, a cylinder head, inlet and discharge valves, an unloading device carried by the cylinder head and including a valve seat formed on the head, a rotary unloading valve cooperating with said seat, a rack carried by said valve, a reciprocable plunger carried by said head, means for effecting reciprocation of said plunger, and gearing connections between said plunger and said rack.

6. In a pump, in combination, a cylinder having a head, means associated with said cylinder for controlling the inlet of fluid thereto and the discharge of fluid therefrom during normal operation, and separate pump unloading means including an unloading valve coaxial with said cylinder for effecting unloading thereof.

7. In a pump, in combination, a cylinder having a head, means associated with said cylinder for controlling the inlet of fluid thereto and the discharge of fluid therefrom during normal operation, and separate pump unloading means including an unloading valve rotatable on an axis in the same line with the cylinder axis for effecting unloading.

8. In a pump, in combination, a cylinder having a head, a piston having a piston rod and reciprocable in said cylinder, means associated with said cylinder for controlling the inlet of fluid thereto and the discharge of fluid therefrom during normal pumping operation, and unloading means for said pump including a rotatable annular unloading valve having a central opening larger than the diameter of said piston rod and surrounding the axis of the cylinder.
